This patent or application file contains at least one drawing executed in color. Copies of this patent with color drawing(s) will be provided by the Office upon request and payment of the necessary fee.

FIG. 1 is a front view of an electronic copying machine showing a first embodiment of our new design with contrast coloration;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof;

FIG. 8 is a front view thereof, shown with the coloration omitted for ease of disclosure;

FIG. 9 is a rear view thereof;

FIG. 10 is a top plan view thereof;

FIG. 11 is a bottom plan view thereof;

FIG. 12 is a right side view thereof;

FIG. 13 is a left side view thereof;

FIG. 14 is a perspective view thereof;

FIG. 15 is a front view of an electronic copying machine showing a second embodiment of our new design;

FIG. 16 is a rear view thereof;

FIG. 17 is a top plan view thereof;

FIG. 18 is a bottom plan view thereof;

FIG. 19 is a right side view thereof;

FIG. 20 is a left side view thereof; and,

FIG. 21 is a perspective view thereof.

The broken lines indicate portions of the electronic copying machine that form no part of the claimed design.
